UNITED STATES PATENT OFFICE.

EDWIN E. CARLSON, OF CHESTER, PENNSYLVANIA.

DRIVING MECHANISM FOR YARN MOISTENERS.

Application filed October 8, 1925. Serial No. 61,265.

In yarn-winding mechanism the yarns require moisture, some yarns requiring a comparatively slight degree of moisture and others requiring a comparatively large degree. It is consequently highly desirable that the winding mechanism be provided with means whereby the amount of moisture taken up by the yarns may be quickly and easily regulated.

10 The object of my invention is to provide a yarn-winding machine with means whereby the yarn moistening mechanism may be quickly and easily adjusted to provide for substantial or minute increase or decrease 15 in the amount of moisture taken up by the yarns.

This object, and other advantageous ends, which will be described hereinafter, I attain in the following manner, reference being 20 had to the accompanying drawings in which

Figure 1 is an end view of a coning machine equipped with my invention,

Figure 2 a fragmentary top plan view of the same,

25 Figure 3 a transverse section on line 3—3 of Figure 1,

Figure 4 a fragmentary front view of the machine, and

Figure 5 a detail of one of the elements 30 employed.

Referring to the drawings, 1 indicates the drive shaft of a coning machine, 2 a cam wheel fixed to the shaft, 3 a gear wheel fixed to the drive shaft, 4 a gear wheel mounted upon a shaft 5 and provided with an eccentric pin 6, 7 a link pivoted at one end to the eccentric pin and at the other end to a crank arm 8 fixed to a rock shaft 9. 10 is an arm adjustably secured to the 35 rock shaft and provided with holes 11 in one of which one end of a link 12 is pivotally secured, the other end of the link being pivotally mounted upon the reduced end 13 of a bolt-nut 14 slidably mounted in a guide 40 arm 15 loosely mounted upon a shaft 16 rotatably mounted in bearings on the frame. A threaded rod 17 is rotatably mounted in the free end of guide arm 15 but held against longitudinal movement therein by 45 a thrust collar 18. Rod 17 takes through a threaded bore 19 in bolt-nut 14 and into a recess 20 in which the bolt-nut is slidable, and is provided at its outer end with a hand bar 21 by which it may be rotated. A 50 ratchet wheel 22 is fixed to shaft 16 and is

adapted to be actuated by a ratchet pawl 23 pivotally mounted on a bolt 24 taking into a bracket 25 extending from guide arm 15. Shaft 16 also carries a yarn engaging element 26, rotatable with the shaft, disposed in the path of the yarn and shown as of fluted and tapered form. A trough 33 adapted to contain the moistening liquid is mounted longitudinally of the frame in such position that a part of shaft 16, or the 60 yarn engaging element thereon, or both, will be immersed in the moistening liquid. 27 indicates the spindle from which the 65 yarn is led and 28 the cone upon which it is wound. I have illustrated but one yarn 70 engaging element but in practice shaft 16 will carry a series of such elements including one for each cone.

I have illustrated at 29 tension mechanism, which may be of the usual type, and I have shown the usual trip arm 30 extending from rock shaft 9 adapted to actuate mechanism, indicated in part at 31, 32, for throwing the cone out of commission in case of breakage of thread. These form no 75 part of the present invention and are shown only to make clear the location of parts with reference to coning machines of the usual type.

In operation, the yarn is led from spindle 27 through tension device 29, over the 80 yarn engaging element 26 to the cone 28. Rock shaft 9 acting through arm 10 and link 12 imparts a rocking movement to guide arm 15. The upward throw of the guide arm 85 90 acting through pawl 23 actuates ratchet wheel 22 and imparts a partial rotation to shaft 16, the extent of this step by step rotary movement, and consequently the extent of the moistened area of the yarn engaging 95 elements, which are brought into contact with the yarn depending upon the extent of the throw of guide arm 15. The extent of this throw may be regulated in two ways, first by adjusting the position of the lower 100 end of link 12 relatively to arm 10, either by means of the series of adjusting holes 11 in arm 10 or by partially rotating the arm 10 on the rock shaft 9 and clamping it in a new position, and second by adjusting the position of bolt-nut 14 in guide arm 15 by means of threaded rod 17 which adjusts the position of the upper end of link 12 relatively to the rocking guide arm. The 105 first affords an adjustment which, though 110

not extensive in fact, is broad compared with that effected by the threaded rod. By making ratchet wheel 22 with a multiplicity of teeth and making the pitch of the thread on rod 18 fine, I provide for any required nicety of adjustment.

While I have described my invention as taking a particular form, it will be understood that the various parts may be changed 10 without departing from the spirit thereof, and hence I do not limit myself to the precise construction set forth, but consider that I am liberty to make such changes and alterations as fairly come within the scope of the 15 appended claims.

Having thus described my invention, what I claim as new and desire to secure by Letters Patent is:—

1. In a yarn winding machine having a 20 rock shaft; a liquid carrying trough disposed adjacent the path of the yarn; a moistening roller extending into the liquid in the trough and secured to a rotatable shaft; a ratchet wheel fixed to the rotatable shaft; a 25 guide arm loosely mounted on the rotatable shaft and carrying a pawl adapted to actuate the ratchet wheel; a rock arm secured to the rock shaft; a link pivotally connected to the rock arm and to the guide arm; means on 30 the rock arm for making coarse adjustments of the ratchet wheel movement, and means on the guide arm for making fine adjustments of the ratchet wheel movement.

2. In a yarn winding machine having a 35 rock shaft; a liquid carrying trough disposed adjacent the path of the yarn; a tapered moistening roller extending into the liquid in the trough and secured to a rotatable shaft; a ratchet wheel fixed to the rotatable shaft; a guide arm loosely mounted on the rotatable shaft and carrying a pawl adapted to actuate the ratchet wheel; a screw adjusted 40 slidably member mounted in the guide arm whereby fine adjustments of the ratchet wheel movement may be made; a link having one end pivotally connected to the slidable member, and a rock arm se-

cured to the rock shaft having apertures in its extending portion for connection to the other end of the link whereby coarse adjustments of the ratchet wheel movement may be made.

3. In a yarn-winding machine, a liquid-carrying trough disposed adjacent the path of the yarn; a rotatably mounted shaft, extending longitudinally of the trough, having a fluted moistening roller fixed thereto extending into the liquid and adapted to engage the yarn; a ratchet wheel fixed to the shaft; a rockable guide arm loosely mounted upon the shaft and carrying a pawl adapted to engage the ratchet wheel; a bolt-nut slidably mounted in the guide arm; a threaded rod taking through the bolt-nut and held against longitudinal movement in the guide arm; a rock shaft; a rock arm mounted on the rock shaft; a link pivotally connected with said rock arm and with the bolt-nut; means for changing the position of the link on the rock arm, and means for actuating the 70 rock shaft.

4. In a yarn-winding machine, a liquid-carrying trough disposed adjacent the path of the yarn; a rotatably mounted shaft extending longitudinally of the trough, having a fluted moistening roller fixed thereto extending into the liquid adapted to engage the yarn; a ratchet wheel fixed to the shaft; a rockable guide arm loosely mounted upon the shaft and carrying a pawl adapted to engage the ratchet wheel; a bolt-nut slidably mounted in the guide arm; a threaded rod taking through the bolt-nut and held against longitudinal movement in the guide arm; a rock shaft; a rock arm mounted on the rock shaft; a link pivotally connected with said rock arm and with the bolt-nut; means for adjusting the position of the link on the rock arm, and means for actuating the 85 rock shaft.

In testimony whereof I have signed my name to this specification.

EDWIN E. CARLSON.
